UNITED STATES PATENT OFFICE.

AUGUST J. HARTFIELD, OF LOS ANGELES, CALIFORNIA, ASSIGNEE TO HELEN A. HARTFIELD, OF LOS ANGELES, CALIFORNIA.

GAS-FUEL-COMBUSTION CHAMBER ATTACHABLE TO HOT-WATER RADIATORS.

1,181,382.

Specification of Letters Patent. Patented May 2, 1916.

Application filed October 23, 1915. Serial No. 59,462.

To all whom it may concern:

Be it known that I, AUGUST J. HARTFIELD, a citizen of the United States of America, residing at Los Angeles, county of Los Angeles, State of California, have invented a certain new and useful Gas-Fuel-Combustion Chamber Attachable to Hot-Water Radiators; and I do hereby declare the following to be a full, clear, and exact description of the invention, such as will enable others skilled in the art to which it appertains to make and use the same.

This invention relates to a gas fuel combustion chamber attachable to hot water radiators to convert the latter into gas heaters.

One object of the invention is to provide a novel and improved combustion chamber which can be readily attached to existing forms of hot water radiators so that fuel gas can be made use of to provide the heating medium.

Another object of the invention is to provide a novel and improved construction for the combustion chamber which prevents a back draft from putting out the gas fire in the combustion chamber.

Further objects of the invention are to provide a novel and improved combustion chamber of the nature specified which can be attached to the ordinary hot water radiator to form a gas fuel heater which is simple in construction, economical to install and maintain, attractive in appearance, clean and odorless in use, convenient and sanitary, and highly effective for its purpose.

Other objects and the advantages of the invention will be apparent to those skilled in the art from a careful consideration of the following description of the preferred construction embodying the invention, taken in connection with the accompanying drawings in which—

Figure 1 is a front elevational view of the improved gas fuel combustion chamber attached to an ordinary hot water radiator—the latter being indicated by dotted lines; Fig. 2 is a sectional view of the combustion chamber, taken on the line 2—2 of Fig. 1; Fig. 3 is an enlarged broken sectional view taken on the line 3—3 of Fig. 2; Fig. 4 is an enlarged broken side view of the lower part of the combustion chamber; Fig. 5 is an en-

larged broken sectional view taken on the line 5—5 of Fig. 1; and Fig. 6 shows elevational and bottom plan views of the hood.

As shown in the drawings, the combustion chamber 7 is provided in the upper and lower parts thereof with side openings 8 into which latter are fitted the nipples 9 whereby the combustion chamber 7 can be easily and quickly attached centrally between the sections 10 of an ordinary hot water radiator.

Within the lower part of the combustion chamber 7 is arranged the burner 11 to which is connected one end of the pipe 12 which passes through an opening 13 in one side of the combustion chamber 7 and has on its other end the flaring fitting 14 into which extends the gas fuel supply pipe 15 which latter is provided with the regulating valve 16 and the admission valve 17.

The combustion chamber 7 is provided in the interior thereof with a ledge 18 on which rests the flaring lower end portion 19 of the hood 20, which latter is open only at its upper and lower ends and surrounds the upper part of the burner 11 and has its converging upper end portion 21 extending above the burner 11, as shown. Opposite to the hood 20, the combustion chamber 7 is provided with openings or vents 22. The passageways 11' in the upper part of the burner 11 extend substantially parallel to the inner wall of the hood 20 so that the gas flame is directed away from the inner wall of the hood and toward the opening in the top end of the hood. To permit access to the burner 11 and the placing of the hood 20 on the ledge 18, a door 23 is provided at the lower front part of the combustion chamber 7. Below the burner 11 in the combustion chamber 7 is arranged a T-fitting or piping 24 which is connected to the lower of the nipples 9 and to the outlet pipe 25 which is connected at the rear of the combustion chamber 7 and to which is connected a flue, not shown, which is adapted to carry off the products of combustion to the outside of the building in which the gas radiator is installed.

From the foregoing description the manner of use and the advantages of the invention will be evident to those skilled in the art. It will be seen that the combustion

chamber can be easily and quickly attached to the ordinary hot water radiator to convert the latter into a gas heater.

When the gas heater is in operation, air 5 passes through the fitting 14 and mixes with the fuel gas in the pipe 12. The heated products resulting from burning the gas fuel pass from the burner 11 to the upper part of the combustion chamber 7 and thence 10 pass downwardly through the sections 10 and thence through the piping 24 to the outlet pipe 25. When starting to operate the gas radiator the latter is filled with cold still air which causes a back pressure and consequently 15 a choking effect on the flame of the burner 11, but the vents 22, see Fig. 3, permit the egress of a portion of the cold air so that the heated products of combustion are enabled to quickly force their way through 20 the radiator and remove the still air. When the gas radiator is in full operation some air is drawn into the radiator through the vents 22. The hood 20 shields the burner 11 from back drafts due to gusts of wind by

deflecting the back drafts through the vents 25 22, see Fig. 3, and thus it prevents putting out of the fire in the combustion chamber 7.

I claim

A gas fuel combustion chamber attachable to hot water radiators to convert the latter 30 into gas heaters and provided with vents in the lower part thereof for the purpose set forth, a gas burner in the combustion chamber, and a hood open only at its upper and lower ends, said hood disposed adjacent to 35 said vents and having the lower end portion thereof flaring and surrounding the upper part of the burner and having the upper end portion thereof converging and extending above the burner, said burner provided in 40 the upper part thereof with passageways which extend substantially in parallel to the inner wall of the hood.

In testimony whereof, I have signed my name to this specification at Los Angeles, 45 county of Los Angeles, State of California, this 22nd day of September, A. D. 1915.

AUGUST J. HARTFIELD.
